UNITED STATES PATENT OFFICE.

CHARLES C. MENGEL, SR., OF BAY CITY, MICHIGAN, ASSIGNOR TO CHARLES C. MENGEL, JR., OF LOUISVILLE, KENTUCKY.

AIR AND STEAM FEEDING DEVICE FOR FURNACES.

SPECIFICATION forming part of Letters Patent No. 554,191, dated February 4, 1896.

Application filed September 17, 1895. Serial No. 562,780. (No model.)

To all whom it may concern:

Be it known that I, CHARLES C. MENGEL, Sr., a citizen of the United States, residing at Bay City, in the county of Bay and State 5 of Michigan, have invented certain new and useful Improvements in Air and Steam Feeding Devices for Furnaces, of which the following is a specification, reference being had therein to the accompanying drawings.

10 The invention consists in the construction of an air and steam feeding device for furnaces, and particularly in the construction, arrangement and combination of the various parts, all as more fully hereinafter described.

15 In the drawings, Figure 1 is a sectional perspective of a furnace having my improvements applied thereto. Fig. 2 is a sectional perspective of a part of one of the side walls. Fig. 3 is a horizontal section through the furnace as shown in Fig. 1; and Fig. 4 is a vertical section through a furnace, showing a slightly modified form.

20 A represents a boiler; B, the side walls of the setting; C, the rear wall; D, the bridge-wall; E, the front, and F the grates.

25 The inner faces of the side walls above the grates and the lining of the inclined face G of the bridge-wall I make of bricks H, having on opposite sides the longitudinal grooves I J. These bricks are so laid that the grooves of adjoining bricks will together make longitudinal passages which connect with the interior of the furnace by the slots K, formed by leaving out a portion of the cement between the bricks or otherwise. These grooves 30 on opposite sides of the brick are in different vertical planes, so as not to unduly weaken the bricks. These passages may be made by building fire-clay walls with paper-tubes 35 therein. The paper-tubes burning out will leave passages of the desired size, or where it can be done, metal pipes or castings may be employed to conduct the air and steam.

40 Connecting into the passages formed in the bricks of the bridge-wall are the supply-passages J', which preferably lead to the back wall and through the brickwork in front

thereof, so that their contents may become highly heated before reaching the delivery-jets into the furnace. These supply-passages 50 may and preferably do form continuations of the side passages. These side passages are open at their outer ends and provided with a funnel-shaped mouth L, opposite which are the steam jets M, to which steam is supplied 55 from the boiler by the valve-controlled pipe N, forming an air-injector.

Steam being discharged through the jets into the funnels L will draw in air with it, and the commingled air and steam will be 60 distributed through the passages described, being heated during transit and finally discharged through the slots K into the furnace to aid in producing smokeless combustion.

65 In Fig. 4 I have shown the bricks with vertical passages arranged in an ordinary furnace without a boiler. In this construction I supply water from any suitable source which, in passing slowly through the heated passages in the brickwork, will be formed into steam 70 and discharge into the furnace. In this construction I place a check-valve O in the supply-pipe to prevent the back-pressure of the steam blowing the water back and to control the supply of water. The back-pressure due 75 to generation of steam in the passages shuts the valve which will be opened when the pressure is reduced to let in another supply of water.

What I claim as my invention is—

80 The combination with a furnace having in its side walls steam and air passages and slots opening into the combustion-chamber from said passages and having a bridge-wall also provided with a similar passage and slots and further provided with a supply-passage passing 85 to the rear of the furnace and joining said side-wall passages, of a steam and air supply for said passages, substantially as described.

In testimony whereof I affix my signature in presence of two witnesses.

CHARLES C. MENGEL, SR.
